MOUTHPIECE FOR ALL BRASS MUSICAL INSTRUMENTS

Aaron S. Hulsaver, Brooklyn, N. Y.

Application September 25, 1940, Serial No. 358,329

5 Claims. (Cl. 84—398)

My invention relates to mouthpieces for musical instruments and refers more particularly to mouthpieces for bugles, cornets, etc.

One object of my invention is to provide a mouthpiece wherein the sound chamber is provided with a series of steps from the inlet of the bell to the entrance into the throat.

Another object of my invention is to provide a mouthpiece wherein the sound chamber is provided at its inlet with an undercut formed to create a suction holding the lips of the player firmly in place and a series of sharply defined steps from the inlet of the bell to the entrance of the throat.

15 A still further object of my invention is to provide a mouthpiece wherein the sound chamber is provided with a sharply defined undercut portion under the inside periphery of the bell lip and a series of radially arranged steps rounding 20 into each other providing no sharp corners.

The particular object of my invention of this type of mouthpiece which is one that will enable any one who plays the bugle (especially those who play in the Army) trumpet, cornet etc., to 25 obtain very sharp, clear, piercing, penetrating notes or tones, no matter how any person may blow into the mouthpiece, because the formation or construction of the roof of the mouth and the teeth of most every player are not just alike, 30 so that in this invention the column of air passing through the vibrating lips of the player will successively strike the substantially flat portion of the steps in the tone chamber and will vibrate on these steps and the vibrations will pass into

35 the throat of the mouthpiece or the outlet of the said tone chamber which will thus produce very sharp, clear, piercing and penetrating notes or tones and, furthermore, said vibrations, notes or tones will be increased, multiplied, and amplified.

40 fixed in the said tone chamber for the reason that the lips of the player are held in seal in and against the rim of said mouthpiece, which is out and overhanging the tone chamber, producing a partial vacuum under the said overhanging-

45 the-tone-chamber-rim and therefore no vibrations or air can escape from the lips or the corners of the mouth of the player but must pass through the tone chamber and the throat of said 50 mouthpiece into the bugle, trumpet, cornet, trombone, baritone horn, or other horns of the like character and produce a result never before obtained in any musical instrument in this class.

I attain these objects preferably by the means 55 illustrated in the accompanying drawing where-

in similar parts are referred to by like numerals throughout the several views, in which,

Figure 1 is a section of a mouthpiece with sharply undercut portions.

Figure 2 is a section of a mouthpiece with 5 rounded steps.

In Figure 1, the body 1, is preferably round, tapering at 2, toward the outlet and on the inlet end 3, is a bell shaped portion providing a tone chamber 4, a throat 5, and a tapered portion 6, 10 tapering toward the outlet end.

The bell portion 3, has a rounded outlet 7, that is sharply undercut at 8, and a series of steps 9, having sharp corners 10.

15 In Figure 2, the body 10, is similar but not exactly the same as in Figure 1, being of different construction and of different proportions and has an outside tapered portion 11, an inside tapered portion 12, a throat 13, and a relatively deep tone chamber 14, a rounded lip 15, sharply 20 undercut at 16 and a series of steps 17, that round into each other at 18.

This rounding away of the steps into each other does away with all the sharp corners except at 16, where a sharp corner is required to 25 produce a partial vacuum.

Having thus illustrated and described the preferred embodiment of my invention, I do not wish to limit myself to the exact construction or arrangement of parts shown, since it is evident that modifications may be made therein without departing from the spirit of the invention or scope of the claims.

I claim:

1. In a mouthpiece for musical instruments, 35 a mouthpiece having a tapered shank, a bell shaped tone chamber, an undercut portion on the inside periphery of the said bell shaped portion, and a series of sharply cut graduated steps therein.

2. In a mouthpiece for musical instruments, 40 a mouthpiece having a round body with a beaded inlet, an undercut portion on the inside periphery of said bell shaped portion, a shank on the said bell shaped portion and a series of sharply 45 cut substantially flat steps therein.

3. In a mouthpiece for musical instruments, 50 a mouthpiece with a tone chamber and a throat, said mouthpiece having a round body and a shank, tapered on one end, a bell shaped tone 55 chamber with a beaded outlet on the other end, an undercut portion on the inside periphery of the said bell shaped portion and a series of sharply cut steps decreasing in diameter towards said throat therein spaced apart from said throat. 55

4. In a mouthpiece for musical instruments, a mouthpiece with a tone chamber and a throat, having a round body and a shank, said body tapered on the inside on one end, a bell shaped tone chamber on the other end with a beaded outlet, an undercut portion on the inside periphery, undercut sharply, of the said bell shaped portion and a series of sharply cut graduated, substantially flat steps therein.
5. In a mouthpiece for musical instruments,

a mouthpiece having a tone chamber and a throat and a round body with a tapered shank, said bell shaped tone chamber having a beaded outlet, a sharply undercut portion on the inside periphery of said bell shaped portion and a series of steps substantially flat rounding smoothly into each other presenting no sharply cut portions within the said tone chamber.

AARON S. HULSAVER. 10
